FIG. 3.

Patented Nov. 21, 1922.

UNITED STATES PATENT OFFICE.

PERCIVAL J. WOOD, OF PATERSON, NEW JERSEY.

METHOD OF FORMING PRINTING SURFACES.

Application filed August 19, 1921. Serial No. 493,544.

To all whom it may concern:

Be it known that I, PERCIVAL J. Wood, a citizen of the United States, residing at Paterson, in the county of Passaic and State 5 of New Jersey, have invented certain new and useful Improvements in Methods of Forming Printing Surfaces, of which the following is a specification.

In my application Serial No. 490,225 I 10 have set forth and claimed a method of forming graded incisions in a surface to be used in printing, either directly as the printing surface or in the forming of the printing surface by the etching process, whereby 15 graded-tone effects, as clouded or mottled effects, splotches or stripes, may be brought out in the printing, the same consisting broadly in forcing into such surface the acting faces of an assembly of gravers while 20 maintaining said assembly in convergent relation to said surface, and I have set forth that this maintaining of the gravers-assembly in convergent relation to the surface to be treated may be accomplished by supporting 25 the same at a higher elevation than said surface, or it may be accomplished by making the relative forms of the the surface of the gravers-assembly and the surface to be treated such that one is convex and they do 30 not conform, claiming in said application the former of these two and reserving for this application the latter, which I accordingly describe and claim herein as follows, referring, first, to the accompanying drawings 35 wherein—

Figure 1 shows a tampon used in performing my method;

Figure 2 is a sectional view on a magnified scale of a fragment of the same and 40 the surface to be treated at the moment of forcing the tampon into said surface; and

Figure 3 shows the effect produced in the surface treated by application of the tampon thereto.

1 is a tampon, pad or other body whose 45 form is normally convex and is here shown as having a fabric exterior, the fabric being of such coarseness that the bends l' of its threads will make more or less distinct 50 incisions in a yieldable surface if the fabric be forced thereinto, such bends in the present instance being taken as the gravers. A is the surface to be treated, being here a

varnish coating on a harder surface g (as copper), which may be the surface of 55 a plate or cylinder. Whether surface A be taken as a plane or cylinder (in which latter case Fig. 2 would show a longitudinal section) it and the surface formed by the acting faces of the assembly of gravers l' 60 do not conform; that is to say, these surfaces are so formed that one (here the surface of the gravers-assembly) is normally convex and if they be brought together only a limited part of each can initially contact 65 with the other.

If, then, they be brought together with sufficient force so that the gravers incise the surface A, the incisions will be graded, as at m at the right of Fig. 2 (see also the 70 margins of the splotches shown in Fig. 3), because of the convergence that exists between the two surfaces. This is primarily a matter of the relative forms of the two surfaces, to wit, one of them (the surface 75 of the gravers-assembly in the present example) being convex and the other not conforming thereto; the effect produced will be modified by other circumstances, such as whether or not the tampon is yielding, the 80 degree of force used and how it is applied, as by a blow or by pressure, and whether or not the gravers, after entering the surface A, encountered resistance such as that afforded the harder material g . 85

In actual practice, however, I have formed the tampon of a wad of indiscriminately massed fabric of suitable coarseness or of a wad of any other appropriate material covered with fabric of suitable coarseness so 90 that it will be yieldable in nature. It may form a single convexity, or a plurality of them as actually shown in the drawing. It is wetted with turpentine or some other solvent of the surface A (the only essential being that said surface shall be yieldable to the gravers l' formed by the fabric of the tampon) and then pressed against said surface so that the gravers incise the same. The result is that at the margin of the spot 95 or place where the pressure is applied the incisions will be graded, increasing in size from the extreme outside of the margin inward as shown in Figs. 2 and 3, the latter figure also showing graded areas n due to 100 forming the tampon with a plurality of con-

vexities so that there will be graded incisions left around the spot or place where each such convexity leaves its impression.

When the tampon is formed of yielding material one advantageous result is that different applications thereof to different places on the surface to be treated will produce divers effects, that is, impresses left by the tampon will have different configurations and different tone-effects, which it is one of the particular objects of my invention to produce.

It will be understood that in the example herein shown the surface A is taken as the coating of a body g which is to form the actual printing surface and that after such coating or surface A has been treated in the way explained it will have applied thereto a suitable acid or mordant which will act to etch the surface of the body g where the incisions have exposed it, whereupon the coating will be removed.

However, my invention is not limited to the presence of any surface back of the surface (A) being treated and acting to modify the action of the gravers, as the surface g actually does in the example herein set forth, to wit, by limiting the depth of the incisions and so, by causing the yielding gravers to spread or expand, increasing more or less the area of each incision.

Having thus fully described my invention, what I claim as new and desire to secure by Letters Patent is:

1. In the art of printing, the method of producing the herein-described graded incisions in the surface to be treated which consists in forming said surface and the surface formed by the acting faces of the gravers of a gravers-assembly so that one will be normally convex and when they are brought together only a limited part of each can initially contact with the other and in then forcing said surface of the gravers-assembly against the surface to be treated so that the acting faces of the gravers will enter the latter.

2. In the art of printing, the method of producing the herein-described graded incisions in the surface to be treated which consists in forming said surface and the surface formed by the acting faces of the gravers of a yielding gravers-assembly so that one will be normally convex and when they are brought together only a limited part of each can initially contact with the other and in then forcing said surface of the gravers-assembly against the surface to be treated so that the acting faces of the gravers will enter the latter.

In testimony whereof I affix my signature.

PERCIVAL J. WOOD.
